CLOTHES-WASHING MACHINE

George P. Castner, Webster City, Iowa

Application October 18, 1949, Serial No. 122,118

12 Claims. (Cl. 68—21)

1

The present invention relates to clothes washing machines, and more particularly, to improved clothes washing machines of the character of that disclosed in the copending application of George P. Castner, Serial No. 110,570, filed August 16, 1949, and now abandoned.

Fundamentally, the clothes washing machine disclosed in the Castner application mentioned comprises an upstanding tubular housing formed of sheet metal, a top wall supported in the upper end of the housing, and a tub arranged in the upper portion of the housing and secured directly to the top wall, the top wall and the tub having registering top openings respectively formed therein to accommodate placement and removal of the clothes with respect to the tub. Also, the machine comprises washing mechanism including a substantially disk-like dasher arranged in an upstanding position in the tub adjacent to a side wall thereof and mounted for operation directly on the side wall. An electric drive motor is arranged below the tub and is supported directly thereby, and a drive connection is provided between the motor and the dasher. In the machine, the top wall, the tub, the dasher, the motor and the drive connection constitute a subassembly carried and supported entirely by the upper end of the housing. Further, a cover is mounted on the top wall for movements between open and closed positions with respect to the top openings mentioned. Finally, a hand operated wringer is mounted on the underside of the cover and is movable there-with through the registering top openings between operative and storage positions, the wringer being disposed above the top wall in its operative position when the cover occupies its open position, and being disposed within the tub in its storage position when the cover occupies its closed position.

While this machine is highly satisfactory in operation and economical to manufacture, the necessary handling of the clothes and the manual operation of the wringer are somewhat inconvenient.

Accordingly, it is a general object of the present invention to provide a clothes washing machine of the character described that incorporates a tub provided with a clothes and wash water receiving chamber and an improved power operated water extracting mechanism, whereby, after a washing operation has been performed upon the clothes in the chamber, a water extracting operation may be performed upon the clothes in the chamber, all without handling

2

of the clothes, and entirely by the power operated washing and water extracting mechanisms.

Another object of the invention is to provide in a clothes washing machine of the type noted, a mechanism that is selectively operative initially to adjust the effective volume of the chamber dependent upon the load of the clothes to be washed and that is operative subsequently to effect extraction of the wash water from the clothes after they have been washed.

Another object of the invention is to provide in a clothes washing machine, a water extracting mechanism of the squeeze type that is of improved construction and arrangement so that the operation thereof to express the water from the clothes is substantially independent of the load of the clothes contained in the tub.

A further object of the invention is to provide in a clothes washing machine including washing mechanism and water extracting mechanism, an improved control arrangement for the mechanisms that is so organized that simultaneous operations thereof are prevented in order positively to eliminate the possibility of damage to the clothes by operation of the washing mechanism during operation of the water extracting mechanism.

A further object of the invention is to provide in a clothes washing machine of the character described, an improved upstanding tubular housing that carries and supports from the upper end thereof, as a subassembly, the tub and the operating elements of the machine that are, in turn, carried by the tub.

Further features of the invention pertain to the particular arrangement of the elements of the clothes washing machine and of the elements of the control system therefor, whereby the above-outlined and additional operating features there-of are attained.

The invention, both as to its organization and method of operation, together with further objects and advantages thereof, will best be understood by reference to the following specification taken in connection with the accompanying drawings, in which Figure 1 is a vertical sectional view of a clothes washing machine, taken longitudinally of the tub, and embodying the present invention; Fig. 2 is a vertical sectional view, partly broken away, of the machine, taken transversely of the tub in the direction of the arrows along the line 2—2 in Fig. 1; Fig. 3 is a fragmentary vertical sectional view of the upper portion of the machine, taken transversely of the tub in the direction of the arrows along the line

3—3 in Fig. 1; Fig. 4 is another fragmentary vertical sectional view of the upper portion of the machine, taken transversely of the tub in the direction of the arrows along the line 4—4 in Fig. 1; Fig. 5 is an enlarged longitudinal sectional view of the compound screw device embodied in the water extracting mechanism incorporated in the machine shown in Fig. 1; Fig. 6 is an electric diagram of the circuit control network for the machine shown in Fig. 1; Fig. 7 is a fragmentary vertical sectional view of the upper portion of a modified form of the clothes washing machine embodying the present invention, this view being taken longitudinally of the tub and corresponding to Fig. 1 and illustrating an alternative construction and arrangement of the tub incorporated in the machine; and Fig. 8 is a vertical sectional view of the modified form of the machine, taken transversely of the tub in the direction of the arrows along the line 8—8 in Fig. 7.

Referring now to Figs. 1 to 6, inclusive, of the drawings, there is illustrated a clothes washing machine 10 of the character of that disclosed in the previously mentioned Castner application and embodying the features of the present invention. The machine 10 comprises an upstanding tubular housing 11 of the wrap-around type formed of sheet metal and including connected front and rear walls 12 and 13 and side walls 14 and 15. The edges of the sheet from which the housing 11 is formed are overlapped and seamed in the rear wall 13 as indicated at 16, the overlapped edges of the seam 16 being suitably secured together by spot welding, or the like. The corners joining adjacent ones of the walls 12, 13, 14 and 15 are rounded in order to lend a finished appearance to the housing 11; and the lower edge of each of the walls is flanged inwardly intermediate the two adjacent corners thereof. The lower end of the housing 11 is supported by an arrangement including four feet 17 respectively disposed at the four rounded corners of the housing 11. Each foot 17 comprises two angularly related sections 18 and 19 substantially channel-shaped in cross section and respectively suitably secured by spot welding, or the like, to the lower surfaces of the adjacent flanges provided on the adjacent walls 12, 13, 14 and 15 at the associated rounded corners of the housing 11. Accordingly, the feet 17 reinforce the housing 11 adjacent to the lower portion thereof and at the rounded corners thereof lending rigidity thereto. In each foot 17 the flanges of the section 18 extend downwardly in spaced relation and receive a supporting roller 20, the roller 20 being journaled upon a pin, not shown, extending between and secured to the lower extremities of the flanges of section 18. Accordingly, the housing 11 is directly supported by the four rollers 20 upon a floor, or the like, in order to facilitate mobility of the machine 10 rendering it portable in an obvious manner.

The machine 10 also comprises a top wall 31 that is provided with a downwardly directed marginal flange or skirt 32 that is arranged within the upper open end of the housing 11. Preferably, the top wall 31 is of die cast metal construction and is generally rectangular in plan conforming to the general configuration of the upper open end of the housing 11. The marginal flange 32 is spaced slightly inwardly from the outer boundary of the top wall 31 in order to provide a surrounding shoulder 33 that directly receives the upper edge of the housing 11. Preferably, the outside surface of the flange 32 di-

rectly receiving the upper end of the housing 11 is provided with a slight upward taper toward the shoulder 33 so that when the top wall 31 is placed in the upper open end of the housing 11, a snug fit is secured, whereby the outer surface of the flange 32 is forced into frictional engagement with the adjacent walls of the housing 11 as the top wall 31 is forced downwardly causing the shoulder 33 to engage the upper edges of the walls of the housing 11. Also, the opposite sides of the marginal flange 32 respectively carry two pairs of depending lugs 34 that receive two corresponding pairs of screws 35 respectively extending thereinto and through aligned pairs of openings respectively provided in the upper portions of the side walls 14 and 15. Nuts 36 are provided, on the inner ends of the screws 35 adjacent to the lugs 34 in order positively to anchor the upper ends of the side walls 14 and 15 to the sides of the marginal flange 32 provided on the top wall 31. Also a top opening 37 is formed in the top wall 31, the top opening 37 being generally rectangular in plan. The front edge of the top opening 37 is disposed somewhat further from the front edge of the top wall 31 than is the rear edge of the top opening 37 from the rear edge of the top wall 31, whereby the top opening 37 is disposed somewhat offset toward the rear of the top wall 31. On the other hand, the side edges of the top opening 37 are disposed substantially equally inwardly from the side edges of the top wall 31. Also, a counter-recess 38 is provided in the top wall 31 in surrounding relation with respect to the top opening 37 so as to provide an inwardly directed ledge 39 immediately surrounding the top opening 37.

A tub 40 is arranged in the upper portion of the housing 11 and comprises connected front and rear walls 41 and 42, side walls 43 and 44, and a bottom wall 45. Preferably, the side walls 43 and 44 and the bottom wall 45 are of one-piece continuous construction, the bottom wall 45 being substantially semi-cylindrical and joining the upstanding side wall 43 and 44, providing a throat therebetween. The front wall 41 is provided with a forwardly directed marginal flange 46 arranged within the front ends of the side walls 43 and 44 and the bottom wall 45 and suitably secured in place by line welding, or the like. Similarly, the rear wall 42 is provided with a rearwardly directed marginal flange 47 arranged within the rear ends of the side walls 43 and 44 and the bottom wall 45 and suitably secured in place by line welding, or the like. The upper ends of the front and rear walls 41 and 42 and the side walls 43 and 44 are provided with an outwardly directed marginal flange indicated generally at 48 and disposed below and engaging the lower surface of the ledge 39 provided on the top wall 31. Thus the tub 40 is provided with a top opening indicated generally at 49 surrounded by the marginal flange 48 and registering with the top opening 37 provided in the top wall 31. The tub 40 is supported directly by the top wall 31 by an arrangement including a plurality of screws 50 extending through openings provided in the ledge 39 and threaded into aligned openings provided in the marginal flange 48. The component parts of the tub 40, including the front and rear walls 41 and 42, the side walls 43 and 44 and the bottom wall 45, are formed of suitable corrosion resistant sheet metal, such, for example, as stainless steel.

Also, the machine 10 comprises a top cover 51 that is substantially rectangular in plan, the

cover 51 being pressed from sheet metal, or the like. The cover 51 is operatively associated with the top opening 37 provided in the top wall 31 and is mounted for movements between open and closed positions with respect thereto upon two laterally spaced-apart hinge mechanisms 52 suitably secured mutually to the rear portion of the top wall 31 and to the rear portion of the cover 51. Also, the cover 51 is provided with a marginal flange or rim 53 that extends downwardly and is arranged within the recess 38 provided in the top wall 31 when the cover 51 occupies its closed position engaging the adjacent ledge 39 surrounding the top opening 37 provided in the top wall 31. Further, a depression 54 is provided in the central front portion of the cover 51; and a handle 55 formed of sheet metal, or the like, is rigidly secured within the depression 54 in order to facilitate movements of the cover 51. Finally, an opening 56 is formed in the depression 54 for the purpose of venting the interior of the tub 40 below the handle 55 to the exterior when the cover 51 occupies its closed position. In view of the foregoing it will be understood that the cover 51 may be readily moved between its closed and open positions with respect to the top openings 37 and 49 respectively formed in the top wall 31 and in the tub 40 about the hinge mechanisms 52 by utilizing the handle 55, the cover 51 being secured adjacent to the rear thereof to the hinge mechanisms 52, as previously noted. The hinge mechanisms 52 are so constructed and arranged that when the cover 51 occupies its fully open position, it is disposed in a slightly upwardly inclined position with respect to the top wall 31 and thereabove projecting rearwardly beyond the rear wall 13. On the other hand, when the cover 51 occupies its fully closed position, the upper surface thereof is disposed substantially flush with the top wall 31 lending a finished appearance to the machine 10. The ventilation of the interior of the tub 40 through the opening 56 provided in the depression 54 in the cover 51 below the handle 55 to the exterior prevents the accumulation of musty atmosphere in the tub 40 when the cover 51 occupies its closed position.

An upstanding water extracting plate 57 is provided within the rear end of the tub 40 adjacent to the upstanding rear wall 42 and spaced slightly forwardly with respect thereto, the configuration of the plate 57 conforming substantially to that of the rear wall 42. The plate 57 is provided adjacent to the upper end thereof with a rearwardly directed flange 58 engaging both the front surface of the rear wall 42 and the undersurface of the ledge 39 adjacent to the rear edge of the top opening 37 formed in the top wall 31, whereby the front surface of the plate 57 is disposed substantially in vertical alignment with the rear edge of the top opening 37, the plate 57 being secured in place by a series of screws 59 extending through openings provided in the rear portion of the ledge 39 and received in aligned threaded holes provided in the flange 58. The plate 57 may be formed of one-piece die cast construction or pressed directly from a fairly heavy gauge of stainless steel, or the like, the plate 57 being perforated by the provision of a number of holes 60 therein. Further, the position of the plate 57 spaced forwardly with respect to the rear wall 42 is maintained by a series of spaced-apart stanchions 61 disposed therebetween, the rear ends of the stanchions 61 being suitably secured to the ad-

jacent face of the rear wall 42 and the front ends of the stanchions 61 being suitably secured in aligned openings 62 provided in the plate 57. Accordingly, the upstanding rear wall 42 and the upstanding plate 57 define an upstanding space 63 therebetween with which a downwardly extending drain connection 64 formed in the bottom wall 45 of the tub 40 communicates. Further, a substantially cusp-shaped cut-out 65 is formed in the lower portion of the plate 57 and communicating between the principal interior of the tub 40 and the space 63 adjacent to the drain connection 64.

A forwardly directed substantially annular emboss 66 is formed in the central portion of the plate 57 in order to provide a substantially circular recess 67 surrounded thereby, the centers of the emboss 66 and of the recess 67 being substantially coincident with each other and with the arc of the bottom wall 45 of the tub 40. A substantially disk-like dasher plate 68 is arranged within the recess 67 and mounted upon the front end of a drive shaft 69 that extends through aligned openings respectively formed in the rear wall 42 and in the plate 57. More particularly, the drive shaft 69 is supported and journalled for rotation substantially along the longitudinal axis of the tub 40 in bearing structure including complementary sections 70 and 71 respectively disposed interiorly and exteriorly of the rear wall 42 adjacent to the center of the emboss 66, whereby the sections 70 and 71 provide a liquid-tight joint surrounding the opening provided in the rear wall 42 and preventing the escape from the tub 40 of wash water along the drive shaft 69. The rear end of the drive shaft 69 carries a pulley 72 rigidly secured thereto, whereby the drive shaft 69 and the dasher plate 68 may be rotated unidirectionally. The rear wall 42 of the tub 40 is spaced forwardly with respect to the rear wall 13 of the housing 11 and the pulley 72 is arranged in this space.

As best shown in Fig. 4, the dasher plate 68 is rotated unidirectionally in the clockwise direction as viewed from the front face thereof, and carries on its front face three relatively shallow outstanding vanes 73, 74 and 75, the vane 73 being disposed on one side of the center of rotation of the dasher plate 68 and the vanes 74 and 75 being disposed on the other side of the center of rotation of the dasher plate 68 and in radial spaced-apart relation with respect to each other. The vanes 73, 74 and 75 are removed from the center of rotation of the dasher plate 68 and extended in a crosswise to radial direction with respect to the center of rotation of the dasher plate 68, each of the vanes 73, 74 and 75 being tapered and provided with leading and trailing ends with respect to the direction of rotation of the dasher plate 68 so that the leading end of each vane is closer than the trailing end thereof to the front face of the dasher plate 68. For example, the leading ends of the vanes 73, 74 and 75 marked "L" may be in the plane of the front face of the dasher plate 68, while the trailing ends of the vanes marked "T" may be disposed outwardly therefrom, the taper being continuous between the ends "L" and "T". Also, a shallow recess 76 is provided in the front face of the dasher plate 68 between the vanes 74 and 75, this recess 76 assisting in the release of the clothes from the front face of the dasher plate 68 as explained more fully hereinafter. The central portion of the dasher plate 68 is provided with a forwardly directed boss 77 having a hole

18 therein that receives the front end of the operating shaft 69, as previously noted. Also, a substantially annular resilient element 79 formed of rubber, or the like, is suitably secured upon the peripheral edge of the dasher plate 68 in order to prevent working of the clothes contained in the tub 40 between the dasher plate 68 and the plate 51 and the consequent breakage of buttons, or the like, carried upon the clothes.

Also, the machine 10 comprises an upstanding water extracting plunger 80 arranged within the front end of the tub 40 and adjacent to the upstanding front wall 41, the plunger 80 being movable toward and away from the opposed upstanding plate 51. The plunger 80 is spaced rearwardly of the front wall 41 and has a configuration conforming substantially to that of the front wall 41 as well as to that of the plate 51. Specifically, the plunger 80 comprises a relatively rigid metal backing plate 81 carrying a substantially L-shaped guide foot 82 adjacent to the lower end thereof, which guide foot 82 is provided with a forwardly extending toe 83 arranged in a longitudinally extending guide channel or groove 84 formed in the lowermost portion of the bottom wall 45 and extending from a position adjacent to the front wall 41 to a position adjacent to the rear wall 42 and merging into the drain connection 64. Further, the plunger 80 comprises a hollow envelope 85 provided with spaced-apart upstanding walls 86 and 87 and a connecting boundary wall 88 and enveloping a layer or block of compressible material 89. Preferably, the block of compressible material 89 consists essentially of porous sponge rubber, or the like, while the envelope 85 consists essentially of elastic rubber, or the like, the walls of the envelope 85 being impervious to the wash water contained in the tub 40 and sealing the block 89 against the entrance of wash water thereto. The wall 86 of the envelope 85 is directly secured to the adjacent face of the backing plate 81 employing rubber cement, or the like, whereby the face wall 87 of the envelope 85 is disposed in spaced relation with respect to the plate 51 and cooperates therewith to define a clothes receiving compartment 90 therebetween within the tub 40. The boundary wall 88 of the envelope 85 is arranged in spaced relation with the side and bottom walls 43, 44 and 45 of the tub 40 so that it does not drag or rub thereon as the plunger 80 is moved toward and away from the plate 51, the movement of the plunger 80 with respect to the plate 51 being guided by the toe 83 of the foot 82 sliding in the guide channel 84 formed in the bottom wall 45 of the tub 40. Accordingly, it will be understood that the effective volume of the compartment 90 within the tub 40 and disposed between the face wall 87 of the plunger 80 and the face of the plate 51 may be selectively adjusted dependent upon the load of the clothes to be washed by selectively moving the plunger 80 toward or away from the plate 51 as explained more fully below. A substantially centrally disposed opening 91 is formed in the front wall 41; and a flexible boot 92 formed of elastic rubber, or the like, is arranged between the front wall 41 and the backing plate 81, the boot 92 being of substantially annular accordion construction, one end of the boot 92 being sealed in liquid-tight relation to the adjacent surface of the front wall 41 surrounding the opening 92 by an arrangement including a ring 93, and the other end of the boot 92 being sealed in liquid-tight relation to the adjacent surface of the backing

plate 81 by an arrangement including a ring 94. Preferably the adjacent one end of the boot 92 is clamped between the front wall 41 and the ring 93, and the adjacent other end of the boot 92 is clamped between the backing plate 81 and the ring 94. In any case the boot 92 seals the front wall 41 to the backing plate 81 preventing the escape of wash water from the tub 40 through the opening 91 as the plunger 80 is moved in the tub 40 toward and away from the plate 51.

For the purpose of moving the plunger 80 toward and away from the plate 51, mechanism is provided in the machine 10 that includes a compound screw device 95 arranged substantially along the longitudinal axis of the tub 40 and extending through the opening 91 formed in the front wall 41 and within the boot 92. As best shown in Fig. 5, the compound screw device 95 comprises a central shaft 96 provided with an end portion 97 supporting a surrounding sleeve 98, that, in turn, supports a surrounding sleeve 99, that, in turn, supports a surrounding barrel 100. The rear end of the barrel 100 terminates in an outwardly directed flange 101 that is directly secured by a series of screws 102 to the adjacent central portion of the backing plate 81 of the plunger 80. The exterior surface of the end portion 97 is threaded and engages cooperating threads provided in the interior surface of the surrounding sleeve 98; the exterior surface of the sleeve 98 is threaded and engages cooperating threads provided in the interior surface of the surrounding sleeve 99; and the exterior surface of the sleeve 99 is threaded and engages cooperating threads provided in the interior surface of the barrel 100. The elements 97, 98, 99 and 100 may be of die cast construction and the cooperating threads provided therein are pitched in the left-hand direction so that when the shaft 96 is rotated in the clockwise direction, as viewed from the front of the machine 10, the elements 97, 98, 99 and 100 are expanded with respect to each other moving the plunger 80 toward the plate 51. In order to insure that the end portion 97 is not threaded toward the right completely through the cooperating sleeve 98, an annular collar 102' is provided adjacent to the left-hand end thereof that cooperates with the adjacent end of the sleeve 98; in order to insure that the sleeve 98 is not threaded toward the right completely through the cooperating sleeve 99, an annular ring 103 is provided adjacent to the left-hand end thereof that cooperates with the adjacent end of the sleeve 99; and in order to insure that the sleeve 99 is not threaded toward the right completely through the cooperating barrel 100, an annular ring 104 is provided adjacent to the left-hand end thereof that cooperates with the adjacent end of the barrel 100. In order to insure that the end portion 97 is not threaded toward the left completely through the cooperating sleeve 98, an annular ring 105 is provided on the front end thereof that cooperates with a counterbore 106 formed in the front end of the cooperating sleeve 98 and ultimately engages an annular shoulder 107 disposed between the threaded portion of the sleeve 98 and the counterbore 106; in order to insure that the sleeve 98 is not threaded toward the left completely through the cooperating sleeve 99, an annular ring 108 is provided on the front end thereof that cooperates with a counterbore 109 formed in the front end of the cooperating sleeve 99 and ultimately engages an annular shoulder 110 disposed between the threaded portion of the sleeve 99 and the counterbore 109; and in order to

insure that the sleeve 98 is not threaded toward the left completely through the cooperating barrel 100, an annular ring 111 is provided on the front end thereof that cooperates with a counterbore 112 formed in the front end of the cooperating barrel 100 and ultimately engages an annular shoulder 113 disposed between the threaded portion of the barrel 100 and the counterbore 112.

In the arrangement of the device 95, the end portion 97, the sleeves 98 and 99 and the barrel 100 may be approximately 6 inches long, and the counterbores 106, 109 and 112 respectively formed in the sleeves 98 and 99 and in the barrel 100 may be approximately 4 inches long. Thus, the sleeve 98 may move approximately 4 inches with respect to the end portion 97 from its nested position thereon toward the right before the ring 105 engages the shoulder 107; the sleeve 99 may move approximately 4 inches with respect to the sleeve 98 from its nested position thereon toward the right before the ring 108 engages the shoulder 110; and the barrel 100 may move approximately 4 inches with respect to the sleeve 99 from its nested position thereon toward the right before the ring 111 engages the shoulder 113. Accordingly, the device 95, although occupying an over-all distance, when collapsed, of approximately 6 inches, is capable of an expansion of approximately 12 inches, while retaining rigidity between the component elements 97, 98, 99 and 100 from end-to-end thereof. Also, in the arrangement the sleeve 98 may move completely in either direction its full stroke with respect to the end portion 97 before the sleeve 98 begins to move with respect to the sleeve 99; and the sleeve 99 may move completely in either direction its full stroke with respect to the sleeve 98 before the barrel 100 begins to move with respect to the sleeve 99; all dependent upon the relative amounts of friction in the cooperating sets of threads.

The dimensions of the screw device 95 providing the 12 inch stroke thereof, as explained above, are appropriate when the tub 40 has the approximate dimensions set forth below. When the screw device 95 occupies its fully retracted position as shown in Fig. 1, the distance between the face of the plunger 80 and the face of the plate 57 may be 10 inches; the distance between the face of the plate 57 and the rear wall 42 may be 1 inch; the thickness of the plunger 80 between the face thereof and the backing plate 81 may be 4 inches; and the distance between the backing plate 81 and the front wall 41 may be 1½ inches. Thus the distance between the front wall 41 and the rear wall 42 may be 16½ inches; the distance between the front wall 41 of the tub 40 and the front wall 12 of the housing 11 may be 7½ inches; and the distance between the rear wall 42 of the tub 40 and the rear wall 13 of the housing 11 may be 4 inches. The principal diameter of the bottom wall 45 through the longitudinal center of the operating shaft 69 may be 18 inches; the distance between the marginal flange 48 provided about the top opening 49 in the tub 40 and the longitudinal center line of the dasher plate 68 may be 10½ inches; and the width of the throat between the side walls 43 and 44 of the tub 40 may be 15 inches. Finally, the diameter of the dasher plate 68 may be approximately 5¾ inches.

The screw device 95 is supported upon the tub 40 by an arrangement including two substantially U-shaped straps 114 and 115 arranged in crossing relation between the front wall 41 of the

tub 40 and the front wall 12 of the housing 11. More particularly, the two straps 114 and 115 cross each other adjacent to the longitudinal center line of the tub 40 and carry at the cross a bearing 116 that supports the shaft 96 of the screw device 95. The strap 114 comprises two longitudinally extending legs 117 and 118 lying along two diametrically disposed exterior surfaces of the cylindrical bottom wall 45, the leg 117 being disposed adjacent to the side wall 43 and the leg 118 being disposed well below the side wall 44. Similarly, the strap 115 comprises two longitudinally extending legs 119 and 120 lying along two diametrically disposed exterior surfaces of the cylindrical bottom wall 45, the leg 119 being disposed adjacent to the side wall 44 and the leg 120 being disposed well below the side wall 43. Thus the upper legs 117 and 119 are disposed above the lower legs 118 and 120, an angle of approximately 60° being subtended between the legs 117, 120 and between the legs 119, 118. The rear ends of the legs 117, 118, 119 and 120 are bent over to provide hooks that overhang and engage the junction between the rear edge of the bottom wall 45 and the flange 47 provided on the rear wall 42; and, likewise, the front ends of the legs 117, 118, 119 and 120 carry fixtures constituting hooks that overhang and engage the junction between the front edge of the bottom wall 45 and the flange 46 provided on the front wall 41. The hooks 117a and 120a respectively provided on the rear ends of the legs 117 and 120 and the fixtures 117b and 120b respectively carried by the front ends of the legs 117 and 120 are illustrated in Fig. 1. Finally, front and rear thrust collars 121 and 122 are respectively carried by the shaft 96 of the device 95 on opposite sides of the bearing 116; and a pulley 123 is secured to the extreme front end of the shaft 96. The front wall 41 of the tub 40 is arranged in spaced relation with respect to the front wall 12 of the housing 11, and the screw device 95 and the pulley 123 are arranged in this space, the screw device 95 projecting from this space through the opening 91 formed in the front wall 41 into the tub 40 and into engagement with the backing plate 81 of the plunger 80.

Further, the machine 10 comprises a longitudinally extending supporting plate 124 disposed below the tub 40 and supported thereby by an arrangement including two laterally extending and longitudinally spaced-apart straps 125 and 126, that are, in turn, carried by two laterally spaced-apart and longitudinally extending straps 127 and 128 that are secured directly to the bottom wall 45 of the tub 40. More particularly, the rear ends of the straps 127 and 128 are bent over to provide hooks that overhang and engage the junction between the rear edge of the bottom wall 45 and the flange 47 provided on the rear wall 42; while the front ends of the straps 127 and 128 are bent over to provide hooks that overhang and engage the junction between the front edge of the bottom wall 45 and the flange 46 provided on the front wall 41. The hooks 127a and 128a respectively provided on the rear and front ends of the strap 127 are illustrated in Fig. 1. The opposite ends of the straps 125 and 126 are suitably secured to the adjacent portions of the straps 127 and 128 by spot welding, or the like; while the supporting plate 124 is suitably secured to the intermediate portions of the straps 125 and 126 employing a series of bolts 129 provided with cooperating nuts 130.

An electric drive motor 131 of the reversible

11

split-phase 110 volts A. C. type is secured to the lower surface of the plate 124 by an arrangement including a series of bolts 132 provided with co-operating nuts 133. The motor 131 is provided with a rotor carrying an operating shaft 134 that projects longitudinally in opposite directions toward the front wall 12 and toward the rear wall 13. The front end of the operating shaft 134 is operatively connected to the bladed element of a fluid drive or coupling mechanism 135 having an enclosing casing 136 that is also bladed and contains a suitable quantity of hydraulic medium, such, for example, as oil. Also, the fluid drive mechanism 135 comprises a forwardly extending operating shaft 137 rigidly secured to the casing 136 thereof and supported by a bearing hanger 138 that is also suitably secured to the plate 124. Further, the plate 124 carries a mechanical clutch mechanism 139 of the solenoid-controlled type and including two clutch plates, not shown, one of the clutch plates being rigidly secured to the shaft 137 and the other of the clutch plates being secured to a shaft 140 supported by a bearing hanger 141 carried by the plate 124. Further, a pulley 142 is rigidly secured to the extreme front end of the shaft 140 in alignment with the pulley 123, the pulleys 123 and 142 being of the V-belt type and interconnected by a V-belt 143. The rear end of the operating shaft 134 is supported by a bearing hanger 144 carried by the plate 124 and has mounted thereupon the rotor, not shown, of a drain pump 145 that is also suitably secured to the plate 124. Further, the plate 124 carries a mechanical clutch mechanism 146 of the solenoid-controlled type and including two clutch plates, not shown, one of the clutch plates being rigidly secured to the operating shaft 134 and the other of the clutch plates being secured to a shaft 147 supported by a bearing hanger 148 carried by the plate 124. Finally, a pulley 149 is rigidly secured to the extreme rear end of the shaft 147 in alignment with the pulley 72, the pulleys 72 and 149 being of the V-belt type and interconnected by a V-belt 150.

The drain pump 145 is provided with a casing having an inlet connection 151 and an outlet connection 152 and is operative to draw wash water into the casing thereof through the inlet connection 151 and to discharge the wash liquid through the outlet connection 152 regardless of the direction of rotation of the rotor thereof by the operating shaft 134 of the motor 131. A drain valve 153 of the solenoid-controlled type is operatively connected to the drain connection 64 communicating with the lower rear portion of the tub 40; and the drain valve 153 is operatively connected to the inlet connection 151 of the drain pump 145 by a short section of flexible hose 154 formed of rubber, or the like. Similarly, the outlet connection 152 of the drain pump 145 is connected by a section of flexible hose 155 formed of rubber, or the like, to the exterior, the hose 155 projecting through an opening 156 formed in the rear wall 13 of the housing 11 and carrying a fixture, not shown, on the outer end thereof that may be operatively associated with a laundry tray, or other drain plumbing in the laundry room in which the machine 10 is arranged. Finally, a service opening 157 is formed in the front wall 12 of the housing 11 in order to afford access to the pulley 123 and the associated belt 143, the service opening 157 being normally closed by a service cover 158 suitably removably secured in place upon the front wall 12. Similarly, a service opening 159 is formed in the rear

12

wall 13 of the housing 11 in order to afford access to the pulley 72 and the associated belt 150, the service opening 159 being normally closed by a service cover 160 suitably removably secured in place upon the rear wall 13.

For the purpose of controlling the washing mechanism, including the dasher plate 68, an electric control switch 161 of the manually operable two-position type is mounted in an opening 162 provided in the rear left-hand portion of the top wall 31 adjacent to and to the left of the left-hand hinge mechanism 52, the switch 161 being provided with a manual operating handle 163 that is restrained in either one of its two operating positions when operated thereto. For the purpose of controlling the screw device 95, and consequently the position of the plunger 80 with respect to the plate 57, an electric control switch 164 of the manually operable three-position type is mounted in an opening 165 provided in the rear right-hand portion of the top wall 31 adjacent to and to the right of the right-hand hinge mechanism 52, the switch 164 being provided with a manual operating handle 166 that is restrained in any one of its three operating positions when operated thereto. The electric control network for the machine 10 further comprises two electro-magnetic relays 167 and 168 that may be mounted on the upper surface of the plate 124 adjacent to the front end thereof; also, the circuit network for the machine 10 comprises a limit switch 169 arranged between the rear wall 42 and the plate 57 and secured to the flange 58 and positioned substantially centrally with respect to the side walls 43 and 44, the limit switch 169 being provided with a forwardly projecting plunger 170 extending through one of the holes 60 provided in the plate 57 and employed for a purpose more fully explained hereinafter.

The connection and arrangement of the control network of the various elements of the machine 10 will best be understood by reference to Fig. 6, wherein there is illustrated diagrammatically the elements mentioned. In the circuit network, a commercial 60 cycle 110 volts A. C. source is employed, one conductor thereof being grounded in the machine 10 and indicated by the sign "−", and the other conductor thereof being ungrounded in the machine 10 and indicated by the sign "+". The motor 131 is of the split-phase type, as previously noted, and includes a main operating winding 171 and an auxiliary starting winding 172, as well as a centrifugal speed-responsive circuit controller or switch 173 governed by the speed of operation of the operating shaft 134 thereof and operative to interrupt the circuit for energizing the auxiliary winding 172 in response to rotation of the operating shaft 134 at a speed of approximately $\frac{1}{2}$ normal speed or any speed thereabove. The switch 161 comprises six individual springs; and the switch 164 comprises five individual springs. The details of the control network will best be understood in conjunction with the description of the various operations of the machine 10 appearing hereinafter.

Now assuming that the user wishes to wash a given load of clothes, she first seizes the handle 55 and moves the cover 51 into its open position with respect to the top openings 37 and 49 and examines the effective volume of the compartment 90 defined between the plate 57 and the plunger 80. The user may decide that the effective volume of the compartment 90 within the

tub 40 is too large in view of the small load of clothes to be washed; whereupon, she operates the switch 164 from its "off" position into its "contract" position, the switch 161 being in its "off" position. When the switch 164 is thus operated from its "off" position into its "contract" position, a circuit including the 1a contacts of the switch 161, the conductor 174, the contacts X1 of the switch 164, the conductor 177, the contacts 2a of the switch 161 and the conductor 175 is completed for energizing the winding of the relay 167, whereby the latter relay operates to close its contacts. The relay 167 closes at its contacts 1b and 2b circuits for respectively poling the switch conductors 182 and 181 — and +, whereby the auxiliary winding 172 of the motor 131 is energized in a predetermined direction; and the relay 167 closes at its contacts 3b a circuit, including the conductor 188, for energizing the main winding 171 of the motor 131. At this time, in view of the direction in which the auxiliary winding 172 of the motor 131 is energized, the rotor thereof, and consequently the operating shaft 134, are rotated in the clockwise direction as viewed from the front of the machine 10. As soon as the rotor of the motor 131 gains approximately $\frac{1}{2}$ speed, the speed-responsive switch 173 is operated to interrupt the circuit for energizing the auxiliary winding 172 thereof, whereby the motor 131 continues to rotate in the same direction, as previously noted, by virtue of the continued energization of the main winding 171 thereof. Also, when the switch 164 is operated from its "off" position into its "contract" position, there is completed, at the contacts Y1 thereof, a circuit, including the contacts 1a of the switch 161, the conductor 174, and the contacts X1 of the switch 164, for applying positive potential to the conductor 178, whereby the solenoid of the drain valve 153 and the solenoid of the clutch mechanism 139 are energized in multiple. The solenoid valve 153 is operated into its open position in order to permit the drain pump 145 to pump from the tube 40 any wash water that might be contained therein. The clutch mechanism 139 is operated into its clutched position, whereby the shafts 137 and 140 are operatively clutched together. At this time the operating shaft 134 of the motor 131 drives the shaft 137 through the fluid coupling mechanism 135, whereby the driven shaft 140 effects rotation of the pulley 142 in the clockwise direction so that the pulley 123 is rotated in the clockwise direction through the V-belt 143. When the pulley 123 is thus rotated in the clockwise direction, the shaft 96 is rotated in the clockwise direction causing the screw device 95 to expand the elements 97, 98, 99 and 100 with respect to each other, whereby there is exerted between the bearing 116 and the backing plate 57 an expansive force urging the plunger 80 away from the front wall 41 and toward the plate 57, whereby the effective volume of the chamber 90 disposed between the plunger 80 and the plate 57 is reduced.

When the volume of the chamber 90 has been contracted to a size appropriate to the user in view of the load of the clothes to be washed, the user operates the switch 164 from its "contract" position back into its "off" position, thereby to interrupt the previously traced circuits for energizing the winding of the relay 167 and for energizing the solenoids of the clutch mechanism 139 and of the drain valve 153. The relay 167 restores to interrupt, at its contacts 3b, the cir-

cuit for energizing the main winding 171 of the motor 131; and interrupts at its contacts 1b and 2b the paths for poling the switch conductors 182 and 181. When the solenoid of the clutch mechanism 139 is thus de-energized, the clutch mechanism 139 declutches the shafts 137 and 140; and when the solenoid of the drain valve 153 is thus de-energized, the drain valve 153 is returned to its closed position. Of course, rotation of the motor 131 is arrested closing the speed-responsive switch 173, and the machine 10 is now in its rest position with the volume of the compartment 90 in its adjusted position suitable to the user.

Upon examining the effective volume of the compartment 90, the user may decide that the effective volume thereof is too small in view of the large load of clothes to be washed; whereupon she operates the switch 164 from its "off" position into its "expand" position, the switch 161 being in its "off" position. When the switch 164 is thus operated from its "off" position into its "expand" position, a circuit, including the 1b contacts of the switch 161, the conductor 174, the contacts X2 of the switch 164, and the conductor 179, is completed for energizing the winding of the relay 168, whereby the latter relay operates to close its contacts. The relay 168 closes, at its contacts 1c and 2c, circuits for respectively poling the switch conductors 182 and 181 + and —, whereby the auxiliary winding 172 of the motor 131 is energized in a direction opposite to the predetermined direction previously mentioned; and the relay 168 closes, at its contacts 3a, a circuit including the conductor 189 for energizing the main winding 171 of the motor 131. At this time, in view of the direction in which the auxiliary winding 172 of the motor 131 is energized, the rotor thereof, and consequently the operating shaft 134, are rotated in the counterclockwise direction, as viewed from the front of the machine 10. As soon as the rotor of the motor 131 gains approximately $\frac{1}{2}$ speed, the speed-responsive switch 173 is operated to interrupt the circuit for energizing the auxiliary winding 172 thereof, whereby the motor 131 continues to rotate in the same direction, as previously noted, by virtue of the continued energization of the main winding 171 thereof. Also, when the switch 164 is operated from its "off" position into its "expand" position, there is completed, at the contacts Y2 thereof, a circuit, including the contacts 1a of the switch 161, the conductor 174, and the contacts X2 of the switch 164, for applying positive potential to the conductor 178, whereby the solenoid of the drain valve 153 and the solenoid of the clutch mechanism 139 are energized in multiple. The solenoid valve 153 is operated into its open position in order to permit the drain pump 145 to pump from the tub 40 any wash water that might be contained therein. The clutch mechanism 139 is operated into its clutch position, whereby the shafts 137 and 140 are operatively clutched together. At this time, the operating shaft 134 of the motor 131 drives the shaft 137 through the fluid coupling mechanism 135, whereby the driven shaft 140 effects rotation of the pulley 142 in the counterclockwise direction so that the pulley 123 is rotated in the counterclockwise direction by the V-belt 143. When the pulley 123 is thus rotated in the counterclockwise direction, the shaft 96 is rotated in the counterclockwise direction causing the screw device 95 to contract the elements 97, 98, 99 and 100 with respect to

15

each other, whereby there is exerted between the bearing 116 and the backing plate 84 a contractive force urging the plunger 80 toward the front wall 44 and away from the plate 57, whereby the effective volume of the chamber 90 disposed between the plunger 80 and the plate 57 is increased.

When the volume of the chamber 90 has been expanded to a size appropriate to the user in view of the load of the clothes to be washed, the user operates the switch 164 from its "expand" position back into its "off" position, thereby to interrupt the previously traced circuits for energizing the winding of the relay 168 and for energizing the solenoids of the clutch mechanism 139 and of the drain valve 153. The relay 168 restores to interrupt, at its contacts 3c, the circuit for energizing the main winding 171 of the motor 131; and interrupts, at its contacts 1c and 2c, the paths for poling the switch conductors 182 and 184. When the solenoid of the clutch mechanism 139 is thus de-energized, the clutch mechanism 139 declutches the shafts 137 and 140; and when the solenoid of the drain valve 153 is thus de-energized the drain valve 153 is returned to its closed position. Of course, rotation of the motor 131 is arrested and the machine 10 is now in its rest position with the volume of the compartment 90 in its adjusted position suitable to the user.

In view of the foregoing, it will be understood that upon operating, the relay 167 poles the auxiliary winding 172 of the motor 131 for rotation in the clockwise direction; and, upon operating, the relay 168 poles the auxiliary winding 172 of the motor 131 for rotation in the counterclockwise direction. Upon operating, the clutch mechanism 139 operatively clutches the shafts 137 and 140, whereby the expansion or contraction of the screw device 95 is selectively controlled depending upon the direction of rotation of the motor 131. Also, since the fluid coupling 135 is disposed between the drive shaft 134 and the shaft 137, the amount of power that may be transmitted from the motor 131 to the screw device 95 is limited regardless of the direction of rotation of the motor 131. In other words, after the screw device 95 has been moved into its completely expanded position or into its completely collapsed position, the load imposed upon the shafts 140 and 137 is sufficiently great to obtain in the fluid coupling 135 complete slippage between the drive shaft 134 and the shaft 137, thereby preventing injury to the mechanism and the motor 131.

In any case after the user has manipulated the switch 164 in order to adjust the effective volume of the compartment 90 dependent upon the load of clothes to be washed, she places the clothes within the compartment 90, fills the tub 40 with hot or warm wash water or liquid as required by the character of the fabrics to be washed, and then places an appropriate amount of detergent in the wash water contained in the tub 40. Normally, the wash water is placed in the tub 40 so that the head thereof rises somewhat above the upper portion of the annular emboss 66 completely submerging the dasher plate 68. At this time, the cover 51 is returned to its closed position by the user and the switch 161 is operated from its "off" position into its "wash" position. When the switch 161 is thus operated into its "wash" position, there is completed, at the X3 contacts thereof, a circuit, including the conductor 175, for energizing the winding of the relay 75

16

167 in order to cause the latter relay to operate and bring about rotation of the rotor of the motor 131 in the clockwise direction in the manner previously explained. Also, when the switch 161 is thus operated into its "wash" position, there is completed, at the Y3 contacts thereof, a circuit, including the X3 contacts thereof, the limit switch 169, and the conductor 176 for energizing the solenoid of the clutch mechanism 146, whereby the clutch mechanism 146 operates operatively to clutch together the shafts 134 and 141. Accordingly, the operating shaft 134 rotating in the clockwise direction, as viewed from the front of the machine 10, rotates the shaft 147 and the pulley 149 in the clockwise direction, whereby the pulley 72 is rotated in the clockwise direction through the V-belt 150 causing the operating shaft 69 and the dasher plate 68 to be rotated in the clockwise direction. When the dasher plate 68 is thus rotated in the clockwise direction, it moves and rearranges the clothes contained in the compartment 90 formed in the tub 40 in a substantially circular upstanding path. Specifically, the dasher plate 68 lightly grasps the clothes as it is rotated unidirectionally in the clockwise direction, as viewed in Fig. 4, by an angular shearing contact therewith and then quickly discharges the clothes in order that they are moved and rearranged in the substantially circular upstanding path, as previously noted. This angular shearing contact with which the clothes are lightly grasped is effected largely by the disposition of the shallow tapered vanes 73, 74 and 75 provided upon the front face of the dasher plate 68; while this quick discharge of the clothes from the face of the dasher plate 68 is materially facilitated by the shallow recess 76 disposed in the front face of the dasher plate 68 and positioned between the vanes 74 and 75.

After the clothes have been washed by the machine 10, the user operates the switch 161 from its "wash" position back into its "off" position in order to interrupt, at the contacts X3 thereof, the circuit for energizing the winding of the relay 167; and to interrupt, at the contacts X3 and Y3 thereof, the circuit for energizing the solenoid of the clutch mechanism 146. The relay 167 restores in order to arrest operation of the motor 131 in the manner previously explained; and the clutch mechanism 146 brings about declutching of the operating shafts 134 and the shaft 147 when the solenoid thereof is de-energized. Accordingly, rotation of the rotor of the motor 131 is arrested, and the drive connection between the operating shaft 134 and the shaft 147 is declutched in order to prevent further rotation of the dasher plate 68 unidirectionally in the clockwise direction.

In passing it is noted that when the switch 161 occupies its "wash" position, there is interrupted at the contacts 1a and 2a thereof, the cross connections between the switch 161 and the switch 164, whereby the switch 164 is rendered ineffective to control the contraction and expansion of the effective volume of the compartment 90 in the tub 40 at this time. This interlock arrangement prevents inadvertent operation of the switch 164 from exercising any control upon the screw device 95 while the switch 161 occupies its "wash" position.

At this time the clothes contained in the compartment 90 formed in the tub 40 have been washed, and in order to cause the machine 10 to extract the wash water therefrom, the user merely operates the switch 164 from its "off" posi-

tion into its "contract" position, after the switch 161 has been returned from its "wash" position back into its "off" position. When the switch 164 is thus operated into its "contract" position at this time, the relay 167 is operated, the solenoid of the clutch mechanism 139 is energized, and the solenoid of the drain valve 153 is energized, whereby the clutch mechanism 139 effectively clutches the shafts 137 and 140 and the solenoid valve 153 is operated to its open position; all in the manner previously explained. When the solenoid valve 153 is thus operated to its open position, the wash water contained in the tub 40 is drained from the drain connection 64 through the drain valve 153 and the hose 154 into the inlet connection 151 of the drain pump 145, whereby the wash water is pumped by the drain pump 145 through the outlet connection 152 and the hose 155 to the laundry tray or to the drain plumbing in the laundry room in which the machine 10 is located. Also, at this time the rotor of the motor 131 is rotated in the clockwise direction, and the clutch mechanism 139 is operated, whereby the screw device 95 is expanded forcing the plunger 80 toward the plate 57 in the manner previously explained. As movement of the plunger 80 toward the plate 57 continues, the clothes contained in the compartment 90 are compressed between the face of the plunger 80 and the plate 57, whereby the wash water absorbed thereby is expressed therefrom through the holes 60 provided in the plate 57 and falls into the drain connection 64 to be pumped from the tub 40. This water extracting operation is continued, whereby the plunger 80 firmly presses the clothes against the face of the plate 57 and holds the pressure thereon, the ultimate pressure exercised by the plunger 80 upon the clothes being limited by the slipping action in the fluid coupling mechanism 135, as previously explained. After the movement of the plunger 80 toward the plate 57 is arrested by the slipping action of the fluid coupling mechanism 135, the user may hold the clothes in compression between the plunger 80 and the plate 57 merely by restoring the switch 164 from its "contract" position back into its "off" position. When the switch 164 is thus operated back into its "off" position, the relay 167 restores arresting operation of the motor 131, the clutch mechanism 139 effects declutching of the shafts 137 and 140, and the drain valve 153 is returned to its closed position. Even though all of the electric circuits of the machine 10 are interrupted at this time, the pressure upon the clothes between the face of the plunger 80 and the face of the plate 57 may be held for any desired time interval in view of the fact that the screw device 95, being entirely mechanical, remains in its expanded position.

At any time after the water extraction operation has been performed in the machine 10, the user may relieve the pressure upon the clothes by operating the switch 164 from its "off" position into its "expand" position, whereby the electric circuits are controlled bringing about the retraction of the plunger 80 with respect to the plate 57; all in the manner previously explained. After the plunger 80 has been moved away from the plate 57 in order to relieve the pressure upon the clothes, the switch 164 is again returned from its "expand" position back into its "off" position in order again to arrest the operation of the machine 10 and to interrupt all of the electric circuits incorporated therein. At this time the user may open the cover 51 and then remove the

clothes from the compartment 90 so that they may be placed in a drier to prepare them for ironing.

In passing it is noted that when a water extracting operation is being performed in the machine 10, the plunger 80 moves toward the plate 57, whereby the clothes are compressed between the plunger 80 and the plate 57 in order to express the wash water therefrom as explained above, the face of the plunger 80 conforming to the clothes and the dasher plate 68 due to the resiliency of the compressible block 89, whereby the plunger 170 of the limit switch 169 is operated actuating the limit switch 169 into its open circuit position. When the limit switch 169 is operated into its open circuit position, a point in the circuit for energizing the solenoid of the clutch mechanism 146 is interrupted, thereby preventing rotation of the dasher plate 68 when the clothes in the machine 10 are under compression between the plunger 80 and the plate 57. This interlock arrangement is very advantageous in view of the fact that the switch 161 might be inadvertently operated from its "off" position into its "wash" position while the clothes are retained under compression between the plunger 80 and the plate 57, whereby rotation of the dasher plate 68 at this time might damage the clothes. When the switch 161 occupies its "off" position, the switch 164 may be operated from its "off" position into its "expand" position in order to relieve the compression upon the clothes between the plunger 80 and the plate 57 as explained above, whereby the plunger 170 of the limit switch 169 is released permitting the limit switch 169 to return to its closed circuit position in order to restore washing control again to the switch 161.

In view of the foregoing, it will be understood that in the machine 10, the top wall 31, the tub 40, and all of the washing and water extracting apparatus comprises a subassembly supported and carried directly by the upper portion of the housing 11. Specifically, the top wall 31 supports directly the tub 40, and the tub 40 supports the remainder of the washing and water extracting mechanisms.

A modified form of the machine 210 embodying the features of the present invention is illustrated, in part, in Figs. 7 and 8. The modified form of the machine 210 is fundamentally of the same construction as the machine 10 and comprises the upstanding tubular housing 211 formed of sheet metal and supporting the top wall 231 in the upper open end thereof, the top wall 231 having the top opening 237 formed therein. The tub 240 is arranged in the upper portion of the housing 211 and comprises a tubular body 241 providing top, bottom and side walls 242, 243, and 244, 245, the top wall 242 having a top opening 246 formed therein and registering with the top opening 237 formed in the top wall 231. Also, the tub 240 comprises a rear wall 247 that is provided with a rearwardly directed marginal flange 248 arranged within the rear end of the tubular body 241 and suitably secured in place by line welding, or the like. The front end of the tubular body 241 is provided with a surrounding outwardly directed marginal flange 249. The water extracting plate 257 is arranged within the tub 240 adjacent to the rear wall 247 and defining the space 263 therebetween that communicates with the drain connection 264 provided in the bottom wall 243 of the tub 240. The plate 257 is of the construction previously described, and is retained

in place by an arrangement including the stanchions 261. Also, the plate 257 has the substantially annular emboss 266 formed therein providing the substantially annular depression 267 receiving the dasher plate 268 of the construction previously described that is mounted upon the operating shaft 269. The operating shaft 269 is journalled in the bearing arrangement including the complementary sections 270 and 271. The upstanding plunger 280 is arranged in the front end of the tub 240 and cooperates with the upstanding plate 257 to define the clothes receiving compartment 290 therebetween within the tub 240.

The front end of the tub 240 is closed and rendered liquid-tight by an arrangement including a substantially torus-shaped flexible diaphragm 401 formed of flexible rubber, or the like, the marginal edge of the diaphragm 401 being secured to the marginal flange 249 provided on the tub 240 by an arrangement including a surrounding ring 402 and a series of screws 403. The marginal edge of the diaphragm 401 is arranged directly between the marginal flange 249 and the ring 402 and is securely clamped in position therebetween by the screws 403, the screws 403 being received directly in threaded openings formed in the ring 402. The diaphragm 401 is of continuous one-piece construction and extends over the face of the plunger 280 providing an enlarged opening 403 disposed substantially centrally of the longitudinal axis of the tub 240. The plunger 280 further comprises the layer or block of compressible material 289 formed of sponge rubber, or the like, as well as the backing plate 281 to which the screw mechanism 295 is secured, the screw mechanism 295 extending through the central opening 403 provided in the diaphragm 401. In this construction the backing plate 281 and the block of compressible material 289 are disposed forwardly and entirely exteriorly of the front face of the diaphragm 401 comprising the front face of the plunger 280. Also, in this construction the plunger 280 carries adjacent to the lower central portion thereof the guide foot 282 that cooperates with the longitudinally extending guide channel or groove 284 formed in the bottom wall 243 of the tub 240 for the purpose of guiding the movement of the plunger 280 toward and away from the plate 257. Further, in this construction the guide foot 282 may be formed of rubber, or the like, and vulcanized, or otherwise secured, to the front face of the plunger 280.

The screw mechanism 295 is provided with the operating shaft 296 that is supported in the bearing 316 and carries the pulley 323. In this arrangement the straps 314 and 315 that support the bearing 316 are provided with rather short legs that extend toward the rear only behind the marginal flange 249 disposed about the front end of the tub 240. Specifically, the ends of the legs of the straps 314 and 315 are bent inwardly to provide hooks that directly engage the rear face of the marginal flange 249 and are anchored in place by a series of screws 404 extending through openings therein and threaded into openings provided in the ring 402, the hook 315a provided on the end of the leg of the strap 315 being illustrated in Fig. 7.

In this construction the tub 240 carries the supporting plate 324 therebelow upon which there is mounted the electric motor and other elements of the washing and water extracting mechanisms. In this case the plate 324 is supported by the transversely extending brackets

325 and 326, that are, in turn, supported by the longitudinally extending straps 327 and 328 that are secured to the bottom wall 243 of the tub 240. In this arrangement the front ends of the straps 327 and 328 are flanged inwardly to provide hooks that are directly retained in place by cooperating screws 405 threaded into openings provided in the ring 402, the hook 327b provided on the front end of the strap 327 being illustrated in Fig. 7. Further, the top wall 242 of the tub 240 is secured directly to the undersurface of the top wall 231 by an arrangement including a substantially rectangular throat element 406 disposed therebetween, the throat element 406 being secured directly to the upper portion of the marginal flange 249 by a series of screws 407 threaded into openings formed in the ring 402, and secured directly to the top wall 242 by a series of screws 408 threaded into openings formed in the top wall 242 and in the flanges 248 and 258 respectively provided on the rear wall 247 and on the plate 257. Finally, the throat element 406 is directly secured to the ledge 239 carried by the top wall 231 and surrounding the top opening 237 by an arrangement including a series of screws 409. The remainder of the construction of the machine 210 is the same as that of the machine 10 previously described, whereby the tub 240 and all of the washing and water extracting mechanisms carried thereby comprise a subassembly, together with the top wall 231, that is supported in the upper open end of the housing 211.

The operation of the machine 210 is substantially identical to that of the machine 10 previously described; however, in this case, the screw device 295 is expanded and contracted through the central opening 403 provided in the diaphragm 401 effecting movement of the plunger 280 toward and away from the plate 257 for the purpose previously described.

In view of the foregoing it is apparent that there has been provided a portable clothes washing machine that is especially suitable for use in apartments, or the like; which machine is of rugged and economical construction and arrangement and that embodies both washing and water extracting facilities and is efficient in operation and is of attractive appearance and design.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. A clothes washing machine comprising a tub including wall structure and a pair of opposed walls, the space in said tub disposed between said walls constituting a chamber adapted to contain clothes and wash liquid, a dasher arranged in said chamber in a submerged position with respect to the wash liquid contained therein and adjacent to one of said walls and mounted thereon for rotation to effect a washing action upon the clothes contained in said chamber, means for mounting the other of said walls for movements with respect to said wall structure toward and away from said one wall, said other wall cooperating with said wall structure to confine the clothes in said chamber during operation of said dasher, movements of said other wall toward and away from said one wall accommodating adjustment of the volume of said cham-

ber depending upon the load of the clothes to be washed, means for controlling the draining of the wash liquid from said chamber during movement of said other wall toward said one wall into close proximity with respect thereto to effect a squeezing action therebetween upon the clothes contained in said chamber in order to express the wash liquid therefrom, mechanism for selectively moving said other wall toward and away from said one wall, and means for limiting the force exerted by said mechanism upon said other wall in its movement toward said one wall in order to limit the squeezing action between said walls upon the clothes contained in said chamber.

2. A clothes washing machine comprising a tub including wall structure and a pair of opposed walls, the space in said tub disposed between said walls constituting a chamber adapted to contain clothes and wash liquid, a dasher arranged in said chamber in a submerged position with respect to the wash liquid contained therein and adjacent to one of said walls and mounted thereon for rotation, normally operative means for rotating said dasher to effect a washing action upon the clothes contained in said chamber, means for mounting the other of said walls for movements with respect to said wall structure toward and away from said one wall, said other wall cooperating with said wall structure to confine the clothes in said chamber during rotation of said dasher, movement of said other wall toward and away from said one wall accommodating adjustment of the volume of said chamber depending upon the load of the clothes to be washed, means for controlling the draining of the wash liquid from said chamber during movement of said other wall toward said one wall into close proximity with respect thereto to effect a squeezing action therebetween upon the clothes contained in said chamber in order to express the wash liquid therefrom, mechanism for selectively moving said other wall toward and away from said one wall, and means responsive to movement of said other wall toward said one wall and into close proximity with respect thereto for preventing rotation of said dasher in order to prevent damage to the clothes contained in said chamber and undergoing the squeezing action between said walls.

3. A clothes washing machine comprising a tub including wall structure and a pair of opposed walls, the space in said tub disposed between said walls constituting a chamber adapted to contain clothes and wash liquid, a relatively flat disk-like dasher arranged in said chamber in a submerged position with respect to the wash liquid contained therein and adjacent to one of said walls and mounted thereon for rotation to effect a washing action upon the clothes contained in said chamber, said one wall being rigid and the other of said walls being flexible, a rigid backing plate arranged behind said other wall in spaced relation with respect thereto, a layer of compressible material arranged between said other wall and said backing plate, means for mounting said backing plate and said layer of material and said other wall for movements as a unit with respect to said wall structure toward and away from said one wall, said other wall cooperating with said wall structure to confine the clothes in said chamber during rotation of said dasher, movements of said other wall toward and away from said one wall accommodating adjustment of the volume of said chamber depending upon the load

of the clothes to be washed, means for controlling the draining of the wash liquid from said chamber during movement of said other wall toward said one wall into close proximity with respect thereto to effect a squeezing action therebetween upon the clothes contained in said chamber in order to express the wash liquid therefrom, said layer of compressible material accommodating deformation of said flexible other wall to conform substantially to the clothes contained in said chamber and to the outer face of said dasher when said other wall is moved toward said one wall into close proximity with respect thereto, and mechanism operatively connected to said backing plate for selectively moving said backing plate and said layer of material and said other wall as a unit toward and away from said one wall.

4. The clothes washing machine set forth in claim 3, wherein said other wall is formed essentially of a sheet of wash liquid impervious rubber and said layer of compressible material is formed essentially of a block of sponge rubber, and wherein the outer surfaces of said layer of compressible material are sealed against the entry thereto of the wash liquid contained in said chamber.

5. A clothes washing machine comprising a tub including wall structure and a pair of opposed walls, the space in said tub disposed between said walls constituting a chamber adapted to contain clothes and wash liquid, a relatively flat disk-like dasher arranged in said chamber in a submerged position with respect to the wash liquid contained therein and adjacent to one of said walls and mounted thereon for rotation to effect a washing action upon the clothes contained in said chamber, means for mounting the other of said walls for movements with respect to said wall structure toward and away from said one wall, said other wall cooperating with said wall structure to confine the clothes in said chamber during rotation of said dasher, means for controlling the draining of the wash liquid from said chamber during movement of said other wall toward said one wall into close proximity with respect thereto to effect a squeezing action therebetween upon the clothes contained in said chamber in order to express the wash liquid therefrom, a bracket carried by said tub, mechanism arranged between said other wall and said bracket for exerting selective pushing and pulling forces therebetween in order selectively to move said other wall toward and away from said one wall, and means for limiting the forces exerted by said mechanism between said other wall and said bracket.

6. A clothes washing machine comprising a tub including wall structure and a pair of opposed walls, the space in said tub disposed between said walls constituting a chamber adapted to contain clothes and wash liquid, a relatively flat disk-like dasher arranged in said chamber in a submerged position with respect to the wash liquid contained therein and adjacent to one of said walls and mounted thereon for rotation to effect a washing action upon the clothes contained in said chamber, means for mounting the other of said walls for movements with respect to said wall structure toward and away from said one wall, said other wall cooperating with said wall structure to confine the clothes in said chamber during rotation of said dasher, movements of said other wall toward and away from said one wall accommodating adjustment of the volume

of said chamber depending upon the load of the clothes to be washed, means for controlling the draining of the wash liquid from said chamber during movement of said other wall toward said one wall into close proximity with respect thereto to effect a squeezing action therebetween upon the clothes contained in said chamber in order to express the wash liquid therefrom, mechanism selectively operative to move said other wall toward and away from said one wall, an electric motor carried by said tub, electric circuit means for selectively operating said motor, and clutch means for selectively operating said mechanism from said motor.

7. A clothes washing machine comprising a tub including an upstanding end wall and connecting wall structure provided with a top opening, an upstanding perforated wall arranged within said tub adjacent to said end wall and in spaced relation with respect thereto, a drain conduit communicating with the interior of said tub between said end wall and said perforated wall, an upstanding movable wall arranged within said tub in opposed relation with said perforated wall and cooperating therewith to define a chamber therebetween within said tub accessible through said top opening and adapted to contain clothes and wash liquid, an upstanding relatively flat disk-like dasher arranged in said chamber in a submerged position with respect to the wash liquid contained therein and adjacent to said perforated wall and mounted upon said end wall for rotation to effect a washing action upon the clothes contained in said chamber, said movable wall cooperating with said wall structure to confine the clothes in said chamber during rotation of said dasher, the position of said movable wall with respect to said perforated wall accommodating adjustment of the volume of said chamber depending upon the load of the clothes to be washed, movement of said movable wall into close proximity to said perforated wall effecting a squeezing action therebetween upon the clothes contained in said chamber in order to express the wash liquid therefrom, and mechanism for selectively moving said movable wall with respect to said wall structure toward and away from said perforated wall.

8. The clothes washing machine set forth in claim 7, wherein said wall structure and said movable wall carry cooperating guide elements arranged in sliding relation with each other in order to guide the movements of said movable wall with respect to said wall structure toward and away from said perforated wall.

9. A clothes washing machine comprising a tube including an upstanding end wall and connecting wall structure provided with a top opening, an upstanding perforated wall arranged within said tub adjacent to said end wall and in spaced relation with respect thereto, a drain conduit communicating with the interior of said tub between said end wall and said perforated wall, an upstanding flexible wall arranged within said tub in opposed relation with respect to said perforated wall and sealed to said wall structure, said flexible wall cooperating with said end wall to define a chamber therebetween within said tub accessible through said top opening and adapted to contain clothes and wash liquid, an upstanding relatively flat disk-like dasher arranged in said chamber in a submerged position with respect to the wash liquid contained therein and adjacent to said perforated wall and mounted upon said end wall for rotation to effect

a washing action upon the clothes contained in said chamber, said flexible wall being movable with respect to said wall structure toward and away from said perforated wall and said dasher, said flexible wall cooperating with said wall structure to confine the clothes in said chamber during rotation of said dasher, movement of said flexible wall into close proximity to said perforated wall and said dasher effecting a squeezing action therebetween upon the clothes contained in said chamber in order to express the wash liquid therefrom, and means for exerting a force between said tub and said flexible wall in order to move said flexible wall toward said perforated wall and said dasher and into close proximity with respect thereto.

10. A clothes washing machine comprising a tub including an upstanding end wall and connected wall structure provided with a top opening, the end of said wall structure opposite said end wall being open, a perforated wall arranged within said tub adjacent to said end wall and in spaced relation with respect thereto, a drain conduit communicating with the interior of said tub between said end wall and said perforated wall, a movable wall arranged within said tub in opposed relation with respect to said perforated wall and adjacent to the open end of said wall structure, a hollow flexible substantially torus-shaped diaphragm having a center opening and extending between the open end of said wall structure and said movable wall and sealed thereto in order to close the open end of said wall structure, said perforated wall and said movable wall defining a chamber therebetween within said tub accessible through said top opening and adapted to contain clothes and wash liquid, a dasher arranged in said chamber adjacent to said perforated wall and mounted upon said end wall for operation, means for operating said dasher to effect a washing action upon the clothes contained in said chamber, movement of said movable wall into close proximity to said perforated wall effecting a squeezing action therebetween upon the clothes contained in said chamber in order to express the wash liquid therefrom, and mechanism extending from the exterior into the center opening provided in said substantially torus-shaped diaphragm for selectively moving said movable wall toward and away from said perforated wall, said diaphragm preventing the escape of the wash liquid from said tub through the open end of said side wall regardless of the position of said movable wall in said tub.

11. A clothes washing machine comprising a tub including an upstanding end wall and connected wall structure provided with a top opening, the end of said wall structure opposite said end wall being open and terminating in an outwardly directed marginal flange, a perforated wall arranged within said tub adjacent to said end wall and in spaced relation with respect thereto, a drain conduit communicating with the interior of said tub between said end wall and said perforated wall, a flexible movable wall arranged within said tub in opposed relation with respect to said perforated wall and adjacent to the open end of said wall structure, a hollow flexible substantially torus-shaped diaphragm having a center opening and extending between said marginal flange and said movable wall and sealed thereto in order to close the open end of said wall structure, a rigid backing plate arranged within the center opening provided in said sub-

stantially torus-shaped diaphragm and behind said movable wall and in spaced relation with respect thereto, a layer of compressible material arranged between said movable wall and said backing plate, said movable wall and said layer of material and said backing plate being movable as a unit toward and away from said perforated wall, said perforated wall and said movable wall defining a chamber therebetween within said tub accessible through said top opening and adapted to contain clothes and wash liquid, a relatively flat disk-like dasher arranged in said chamber adjacent to said perforated wall and mounted upon said end wall for operation, means for operating said dasher to effect a washing action upon the clothes contained in said chamber, movement of said movable wall into close proximity to said perforated wall effecting a squeezing action therebetween upon the clothes contained in said chamber in order to express the wash liquid therefrom, and mechanism extending from the exterior into the center opening provided in said substantially torus-shaped diaphragm and into engagement with said backing plate for selectively moving said movable wall and said layer of material and said backing plate as a unit toward and away from said perforated wall, said diaphragm preventing the escape of the wash liquid from said tub through the open end of said side wall regardless of the position of said movable wall in said tub.

12. A clothes washing machine comprising an

5 expandible-contractible tub adjustable in volume dependent upon the load of the clothes to be washed, mechanism selectively operative to expand and to contract said tub, a dasher arranged in said tub and operative to effect washing of the clothes contained therein, an electric motor of the reversible type, a drive connection between said motor and said mechanism, said mechanism being responsive to rotation of said motor in one direction to expand said tub and responsive to rotation of said motor in the opposite direction to contract said tub, and means for selectively controlling the direction of rotation of said motor.
